UNITED STATES PATENT OFFICE.

JOHN FRANCIS BOORAEM, OF GREENWICH, CONNECTICUT.

SPRING-BOARD HOLDER.

1,250,951.

Specification of Letters Patent. Patented Dec. 25, 1917.

Application filed May 4, 1917. Serial No. 166,304.

To all whom it may concern:

Be it known that I, JOHN FRANCIS BOORAEM, a citizen of the United States of America, residing in Greenwich, in the 5 county of Fairfield and State of Connecticut, have invented certain new and useful Improvements in Spring-Board Holders, of which the following is a specification.

This invention relates to springboard 10 holders, particularly for use in connection with swimming pools, and has for its object to provide an improved construction of relatively inexpensive character and with efficient appliances for securing the spring- 15 board and effecting proper adjustments. At the same time, it has been my aim to protect against contact with water, all those parts of the apparatus which would be injured thereby.

20 A typical example of my improved springboard holder is shown in the accompanying drawings, in which—

Figure 1 is a side elevation of the new springboard holder;

25 Fig. 2 is a longitudinal vertical section on line 2—2 of Fig. 4;

Fig. 3 is a front elevation;

Fig. 4 is a cross section on line 4—4 of Fig. 2, with parts broken away, and

30 Figs. 5 and 6 are cross sections along the lines 5—5 and 6—6 of Fig. 2, showing the springboard and adjacent parts.

The improved springboard holder comprises a suitable frame made of a lower 35 section 10, which is secured to the floor by anchoring bolts 11, and an upper section 12 connected with the lower section by bolts and nuts 13. The upper section is formed so as to inclose a chamber or cavity 12' for 40 the reception of one end of the springboard (indicated by dotted lines at 14, Figs. 1 and 2). This chamber has a roof inclined lengthwise, downwardly from the opening through which the springboard projects. At the central 45 portion of this roof, in the vicinity of said opening, a transverse dowel pin 12" extends downwardly, and about half way between the longitudinal center and the sides of the chamber 12', longitudinal downwardly projecting springs 15 have their ends secured, as by screws 16 accessible from above, within suitable longitudinal recesses 12a of said roof, the central portions of the springs projecting from said recesses about 50 half way between the two ends of the chamber 12'. At the rear of said chamber, and

preferably in line with the springs 15, lateral abutments or dowels 12b are projected downwardly from the roof.

The upper surface of the lower section 10, 60 in conjunction with the side walls of the chamber 12', forms a guide or track for a traveling clamp or wedge 17, the upper surface of which is parallel to the roof of the chamber 12'. This upper surface is pref- 65 erably not continuous, but formed by the surfaces of three longitudinal ribs or clamping elements 17', which are adapted to engage the springboard from below, while the dowel 12", the springs 15, and the abutments 70 or dowels 12b engage the upper surface of said board.

The wedge or clamp 17 is adjusted longitudinally as follows, in order to hold the springboard firmly in position: At its rear portion, the clamp 17 is provided with two spaced lugs 17" extending downwardly through a suitable longitudinal slot in the lower section 10. These lugs are made with alining openings through which extends 80 loosely the adjusting screw 18, while between said lugs the screw is in threaded engagement with a nut 19, held so that it cannot turn. The screw 18 extends lengthwise of the springboard holder and is mounted to 85 turn in the lower section 10 thereof, longitudinal movement of said screw being prevented by means of collars 18' secured to the screw spindle rigidly and engaging suitable surfaces on the lower section 10. To lock 90 the screw against turning accidentally, I provide a transverse set screw spindle 20, see Fig. 4.

All the parts so far described are preferably made of cast iron, steel or other relatively inexpensive material, with the exception of the nut 19 and the screw 18, which are generally made of bronze. These parts are protected by a waterproof casing or top 21 made of steel or cast iron enameled 100 outside and water proofed inside, secured to the base flange of the lower section 10 by screws 22, and preferably fitted with suitable packing 23 to engage the floor. The upper part of the casing is recessed to receive a layer of cork 24. At one side, the casing has an opening through which access may be had to the set screw or locking screw 20, and normally this opening is closed by a plug 25 set flush, or counter sunk to prevent injuring the limbs. All interior parts 110 of the cast iron are covered with a rust

proof coating. At the front, the casing 21 has two openings, of which the upper one is of rectangular shape for the passage of the springboard end into the chamber 12', said opening therefore being in line with the inclined upper portion of the chamber 12', above the clamp 17. To obtain a tight joint where the springboard passes through this opening, I provide a packing strip or gland 26 of rubber or other suitable material, disposed around the edge of said opening and pressed against a stationary collar 27 (secured by screws 27') by means of a movable inwardly tapering follower 28, adjustable lengthwise by screws 29 and locked in position by nuts 29'. This tapering follower will give the board some amplitude or freedom of vibration. At the lower portion of its front wall, the casing 21 has a round opening for the passage of the feed screw spindle 18, the exposed end of said spindle having a hexagon head 18'' and hand wheel 18^b, or other suitable means for turning it. A collar or sleeve 30, threaded both internally and externally, contains a packing 31 in engagement with the shaft or spindle 18, this sleeve being formed with a flange engaging the inner surface of the casing 21, against which it is drawn by the action of the flanged collar 32 which screws on the outside of the sleeve 30, and engages the outer surface of the casing 21. The packing 31 is compressed by means of a gland 33 screwing into the sleeve 30 and having an angular or milled head for turning it. The parts 25, 27, 28, 18'', 29, 30, 32, 33 are preferably made of brass, but otherwise, the use of this expensive metal may be avoided in my improved construction.

The screws 16 are readily accessible upon removing the casing 21. The upper surfaces of the cast ribs 17' have to be planed in order to obtain a proper fit against the underside of the springboard units, but this is much less expensive than planing the entire top surface of the clamp or slide or traveling wedge 17. Another advantage of this construction is that the friction between the springboard and the wedge is reduced, thus making it easier to push the wedge forward. Lead washers 22' are preferably interposed between the heads of the screws 22 and the casing 21, and this arrangement, together with the packings 23, 26 and 31 will prevent the entrance of water, moisture or vapor into the casing 21, and injury to the parts contained therein. The lead washers 22' prevent injury to the enamel on the casing by the screws. The particular relative arrangement of the springs 15, dowel 12'' and abutments 12^b insures a firm support for the springboard, in conjunction with the action of the clamp 17. The ribs 17' also have a firmer and more efficient hold on the board than an unbroken surface would have,

as the pressure of the clamp is concentrated on these ribs. Furthermore, these ribs 17' are preferably located out of registry with the springs 15 (see Figs. 5 and 6), thus having a tendency to bend the board 14 or 70 its units transversely, and holding it in position more firmly. The central rib 17' registers with the central dowel 12''.

I have illustrated and described a preferred and satisfactory embodiment of my 75 invention, but it is obvious that changes may be made therein within the spirit and scope thereof, as defined in the appended claims.

I claim:

1. A springboard holder having a transverse dowel or cleat and longitudinal springs to engage one side of the springboard, and a movable clamping member to engage the other side of the springboard. 80

2. A springboard holder having a transverse dowel or cleat, longitudinal springs, and lateral dowels or abutments to engage one side of the springboard, and a movable clamping member to engage the other side 90 of the springboard. 85

3. A springboard holder having longitudinal springs and lateral abutments, in line with said springs, to engage one side of the springboard, and a movable clamping member to engage the other side of the springboard. 95

4. A springboard holder provided with longitudinal springs to engage one side of the springboard, and a clamping member 100 provided with longitudinal ribs to engage the other side of the springboard.

5. A springboard holder provided with longitudinal springs to engage one side of the springboard, and a clamping member 105 provided with longitudinal ribs out of registry with said springs to engage the other side of the springboard.

6. A springboard holder provided with spaced longitudinal members adapted to engage one side of the springboard, and spaced longitudinal clamping elements out of registry with the said members to engage the other side of the springboard. 110

7. A springboard holder having a pocket 115 or chamber to receive one end of the springboard, a protecting casing provided with an opening in line with said pocket, and packing means along the edge of said opening.

8. A springboard holder having a pocket 120 or chamber to receive one end of the springboard, means for clamping said end, a protecting casing provided with an opening in line with said pocket, packing means along said opening, an adjusting screw, projecting through said casing for operating the clamping means, and a packing at the point where the screw passes through the casing. 125

9. A springboard holder having a pocket 130 or chamber to receive one end of the spring-

board, a protecting casing provided with an opening in line with said pocket, and an inwardly tapering follower located on the casing at said opening and adapted to give 5 the springboard a certain freedom of deflection.

In testimony, that I claim the foregoing

as my invention, I have signed my name in presence of two subscribing witnesses.

J. FRANCIS BOORAEM.
